Primary Examiner — Bridget L Eland(74) *Attorney, Agent, or Firm* — Dunlap Coddng, P.C.(57) **CLAIM**

The ornamental design for an external fixation alignment gauge, as shown and described.

DESCRIPTION

FIG. 1 is a perspective view of an external fixation alignment gauge showing my new design.

FIG. 2 is a front view thereof.

FIG. 3 is a rear view thereof.

FIG. 4 is a left side elevational view thereof.

FIG. 5 is a right side elevational view thereof.

FIG. 6 is a top plan view thereof; and,

FIG. 7 is a bottom plan view thereof.

The dot-dash broken lines represent the bounds of the claimed design while the evenly spaced broken lines are directed to environment and are for illustrative purposes only; the broken lines form no part of the claimed design. The broken break lines in the drawings indicate that the appearance of any portion of the article between the broken break lines forms no part of the claimed design.
